1897X

D. MELVILLE.
GAS LAMP.

Patented Mar. 18, 1813.

David Melville
Sellers Patent

1897X

The Schedule referred to in their Letters Patent and making part of
the same, containing a description in the words of the said David
Melville himself of his improvement in the Gas Lamp.

The improved Gas Lamp, invented and improved by the sub-
scriber is an apparatus for separating the hydrogenous gas, or inflamm-
able air from the carbon, and less volatile ingredients of coal
for the formation of gas light for the lighting of manufactorys, man-
ualls, streets, theatres, light houses and other buildings, into
more agreeable and less expensive & dangerous manner than has
hitherto been done by any other method, all which objects he
has found can be effected by an apparatus simple in its construc-
tion and easy in its management. The apparatus consists of a
light coal iron retort set in a furnace, with a pipe leading to
a practicable cistern filled with water, and a reservoir or gasometer,
suspended in the cistern, by a rope or chain, leading over pulleys or
cheeves, to a rail containing weights, and pipes or tubes leading
from the gasometer to the apartments where the lights are wanted.

The apparatus being filled the mode of operation is as follows. A
quantity of flat coal is placed in the retort the door shut and sealed
tight, a strong heat being applied by means of a fire lighted in the
furnace; hydrogenous gas, or inflammable air is driven out of the coal
confined in the retort and forced through the water in the cistern, by which
it is purified, having passed through the water it rises up the gas-
ometer until it is filled when it may be reserved for occasional use.

By taking one or more weights off the rail the gasometer will beat so
much the greater weight upon the volume of gas contained in it, which
forces it through the pipes to any distance or in any direction to the lamps
or apertures where the lights are wanted, and by which the flames
are made to burn with more or less force at pleasure. If all the
weights should be taken off the rail, and the flames still not burn

with sufficient force, even a mere weight may be placed on the Caramelo, substantially on the weight of the gas from the apparatus, of the burner remaining in contact with the oxygenous gas of the atmosphere, as it will take fire on the application of a taper, and will continue to burn with a brilliant flame without smothering, as long as there is any gas in the Caramelo. The burner is provided with keys by which each flame may be regulated to give more or less light and the whole (the burner excepting) may be regulated as to the size of the flame as they may be instantaneously extinguished by a single key in the main tube or tube.
